UNITED STATES PATENT OFFICE.

WILLIAM C. MEYER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PRESSER-FOOT MECHANISM FOR SHOE-SEWING MACHINES.

1,299,405.

Specification of Letters Patent.

Patented Apr. 1, 1919.

Original application filed July 29, 1913, Serial No. 781,785. Divided and this application filed February 28, 1916. Serial No. 80,910.

To all whom it may concern:

Be it known that I, WILLIAM C. MEYER, a citizen of the United States, residing at Beverly, in the county of Essex and Commonwealth of Massachusetts, have invented certain new and useful Improvements in Presser-Foot Mechanism for Shoe-Sewing Machines; and I do hereby declare the following to be a full, clear, and exact description of the invention, such as will enable others skilled in the art to which it appertains to make and use the same.

This invention relates to shoe sewing machines, and more particularly to sole sewing machines provided with a straight hook needle and rotatable work support or horn which extends within the shoe, such machines being generally known in the art as machines of the McKay type.

Machines of this type of the usual construction comprise a vertical fixed work-supporting horn and a presser-foot which is lifted automatically a substantially uniform distance from the work during each cycle of operations, regardless of the thickness of the work. The work-engaging position of the presser-foot in such machine varies with the thickness of the work, and the presser-foot actuating mechanism is especially constructed to produce substantially the same upward movement of the presser-foot whatever may be its vertical work-engaging position, as determined by the thickness of the work.

The primary objects of the present invention are to produce an improved presser-foot mechanism for shoe sewing machines of the McKay type, which is simple in construction, which will produce the required uniform upward movements of the presser-foot in a reliable manner, and is not liable to get out of order or to require frequent adjustment as the parts become worn by use.

With these objects in view the invention contemplates the provision of an improved friction clamp, constituting a variable connection between the presser-foot actuating member and the presser-foot, and improved mechanism for locking and unlocking the clamp.

The present application constitutes a division of an application Serial No. 781,785, filed July 29th, 1913, on which

Patent No. 1,177,581, dated March 28, 1916, was granted. 55

The invention will be readily understood from the accompanying drawings illustrating a machine embodying the invention in its preferred form, and from the following detailed description of the construction 60 therein shown.

In the drawings, Figure 1 is a view in front elevation, partly in section, of the head of the machine; Fig. 2 is a view in side elevation, looking from the right, illustrating all except the rear portion of the head of the machine; Fig. 3 is a transverse sectional view showing the presser foot lifting mechanism; and Fig. 4 is a detail view, partly in section, illustrating particularly 70 the variable clamp connection forming part of the presser-foot lifting mechanism.

The machine illustrated in the drawings comprises the usual vertically reciprocating straight hook needle indicated at 2, which during each cycle of operations is projected through the work into position to receive the thread from a looping device located in the tip of the horn. The cast-off for preventing the previously formed loop from catching in 80 the hook of the needle as the needle is retracted is indicated at 4. The work is supported during the sewing operation by the horn 6, which in the present embodiment of the invention is vertically fixed, but is arranged to rotate in the usual manner. The work is fed at intervals during the operation of the machine by the feed point 8, which is projected into the work and is then advanced in the direction of the seam to 90 feed the work.

The parts briefly referred to above have the same construction, arrangement and mode of operation as fully described in original application Serial No. 781,785, and 95 need not be further described in this application. The work is engaged between the upper surface of the tip of the horn and presser-foot 10 which is arranged for vertical movement to accommodate work of 100 varying thicknesses.

The presser-foot 10 is secured to the lower end of a bar 12 which is mounted to slide vertically in suitable guides in the frame. The lower portion of the presser-foot bar 105 slides in a guide in the forwardly project-

ing portion 14 of the frame of the machine, and the upper portion of the bar is reduced to form a cylindrical extension or rod 14^a which is arranged to slide in a sleeve 16 secured in an upwardly and forwardly extending bracket 18 on the frame. The presser-foot is held down on the work by a heavy coiled spring 20 which surrounds the upper cylindrical portion of the presser-foot bar, and engages at its lower extremity a shoulder on said bar, and at its upper extremity the lower end of the sleeve 16. The downward movement of the presser-foot under the action of the spring 20, when no work is in the machine, is limited by the engagement of a nut 22 threaded upon the upper end of the presser-foot bar with the upper end of the sleeve 16. By adjusting the nut 22 on the presser-bar, the vertical position of the presser-foot when no work is in the machine, and the tension of the spring 20, may be varied. The sleeve 16 is threaded into the bracket 18, and may be adjusted vertically to vary the vertical position of the presser-foot when no work is in the machine without varying the tension of the spring 20. The sleeve 16 is held in adjusted position by a lock nut 26. By suitable adjustments of the nut 22 and the sleeve 16, the lower limiting position of the presser-foot may be changed, and the tension of the spring 20 may be adjusted as required by the character of the work which is being operated upon.

As is usual in machines of this type, the presser-foot is lifted during each cycle of operations to free the work from engagement with the upper surface of the horn and permit the work to be fed. It is evident that the vertical position of the presser-foot when in engagement with the work varies with the thickness of the work, and in order that the presser-foot may be lifted from the work substantially the same distance in each cycle of operations, regardless of its vertical position when in engagement with the work, a variable friction clamp connection is provided in the presser-foot lifting mechanism, the relative positions of the parts of which are determined when the presser-foot is down in engagement with the work, and which is locked during the lifting action of said mechanism. In the construction illustrated, the mechanism for lifting the presser-foot comprises an arm 28 secured to a rock shaft 30 and provided at its extremity with a pivoted block 32 which engages in a suitable recess in the presser-foot bar. The rock shaft 30 extends rearwardly substantially parallel with the main shaft of the machine, and a second arm 34 is attached to the rear extremity of said rock shaft. The arm 34 is provided with a recess or pocket 36 (see Fig. 4) at its extremity for the reception of a series of friction leaves 38. A series of friction plates 40 are arranged to

slide through openings in the outer end of the arm 34, and are interfitting between the friction leaves 38. The ends of the friction plates 40 are pivotally connected with a lever 42 which is loosely mounted on the shaft 30, 70 and carries a cam roll 44 which engages a cam groove 46 in the cam disk 48 mounted on the main shaft 50 of the machine. In order to clamp the friction plates 40 to the arm 34 so that they cannot move through 75 said arm when the lever 42 is actuated, a lever 52 is pivoted upon a transverse stud 54 carried by the arm 34, and is provided with a recess adjacent the end of its shorter arm in which engages a projection on the clamping plate 56 which fits in the pocket 36 and engages the face of one of the plates 40. The lever 52 is actuated to force the clamping plate 56 inwardly in the pocket and clamp the friction plates 40 to the arm 34 by means 85 of a coiled spring 58 (see Fig. 4) seated at one end in a recess or bore in the end of the shaft 30, and at the other in a recess in the end of the long arm of the lever 52.

During each cycle of operations, and 90 while the presser-foot is lifted, the lever 52 is actuated to relieve the pressure upon the outer friction plate 40, thereby unlocking the clamp and permitting the presser-foot to be forced down on the work by the coiled 95 spring 20. The unlocking of the clamp permits the friction plates 40 to automatically adjust themselves in the outer end of the arm 34 in accordance with changes in the vertical position of the presser-foot due 100 to variations in the thickness of the work. Before the presser-foot is lifted, the clamp is again locked to connect the cam-actuated lever 42 rigidly with the arm 34 to enable said lever to lift the presser-foot. In the 105 present invention, the lever 52 is actuated positively to unlock the clamp. In the construction illustrated, the end of the longer arm of the lever 52 is recessed to receive one extremity of a strut 60, the other end of 110 which strut is received in a similar recess in the end of a screw 62 threaded into an arm 64 of a lever pivoted on a stud 66. Said lever is provided with a second arm 68 which carries a cam roll 70 which operates in a cam groove 72 in a cam disk 74 secured to the main shaft 50 of the machine. The provision of the spring 58 for actuating the lever 52 to lock the clamp insures the actuation of said lever sufficiently 115 to lock the clamp at all times when the lever is free to move under the action of the spring, and no readjustment of the parts is necessary even when they have become worn by use. The screw 62 is adjusted so that 120 the lever 52 is actuated to an extent somewhat greater than that required to unlock the clamp, thereby eliminating the necessity of frequent readjustments to compensate for wear on the parts. The provision 130

of the series of friction leaves and an interfitting series of friction plates for the clamp, furnishes a large extent of engaging friction surfaces, and enables the clamp to be locked 5 securely with a comparatively light pressure upon the lever 52.

As shown in Fig. 4, the hub of the lever 42 is confined between the arm 34 and an adjacent portion of the frame which forms 10 a bearing for the shaft 30. To take up wear and prevent lateral play of said lever on the shaft, the lever is provided with a bearing sleeve 76 threaded into the hub of the lever, which may be adjusted when the 15 parts become worn.

In order to enable the operator to lift the presser-foot so that the finished work can be removed, and another piece of work inserted in the machine, or so that the work 20 being operated upon can be adjusted, a lever 78 is pivoted upon a stud 80, and carries a roll 82 at its extremity which engages beneath a projection 84 on the arm 34. The other extremity of said lever is 25 connected by means of a treadle rod 86 with a lever located in the base of the machine which is operated from a treadle (not shown).

Having explained the nature and object 30 of the invention, and specifically described one form of machine in which it may be embodied, what is claimed is:

1. A sewing machine, having, in combination, a needle, mechanism for actuating the 35 needle, a work support, a presser-foot, means for lifting the presser-foot during each cycle of operations comprising a variable friction clamp connection, a spring for locking the parts of said clamp, and means for unlock- 40 ing the parts of said clamp to permit a relative adjustment of the parts thereof.

2. A sewing machine, having, in combina-

tion, a needle, mechanism for actuating the needle, a work support, a presser-foot, mechanism for lifting the presser-foot during 45 each cycle of operations, comprising an actuating member, a member through which the presser-foot is actuated from said first member, a variable friction clamp connection between said members, said clamp including a series of friction leaves connected with one of said members, a series of friction plates interfitting with and arranged to slide between said friction leaves and connected with the other of said members, a 50 spring for clamping said friction plates between said leaves, and means for releasing said leaves and plates from clamping engagement.

3. A sewing machine, having, in combination, a needle, mechanism for actuating the needle, a work support, a presser foot, means for lifting the presser foot during each cycle of operations comprising an actuating member; a variable connection between 55 the actuating member and the presser foot having its parts constructed and arranged to lock the presser foot from movement in either direction, a spring for locking the parts of said connection and means for unlocking the parts of said connection during each cycle of operations.

4. A sewing machine, having, in combination, a needle, mechanism for actuating the needle, a work support, a presser foot, means 75 for lifting the presser foot during each cycle of operations comprising a variable connection, a spring for locking the parts of said connection and means for unlocking the parts of said connection while the presser 80 foot is lifted to allow the presser foot to be depressed into engagement with the work.

WILLIAM C. MEYER.
